UNITED STATES PATENT OFFICE.

HOWARD W. POWER, OF DAVENPORT, IOWA.

FOLDING WASHBENCH.

1,153,336.

Specification of Letters Patent. Patented Sept. 14, 1915.

Application filed January 11, 1915. Serial No. 1,524.

To all whom it may concern:

Be it known that I, HOWARD W. POWER, a citizen of the United States, residing at Davenport, in the county of Scott and State 5 of Iowa, have invented new and useful Improvements in Folding Washbenches, of which the following is a full, clear, and exact description.

My invention relates to improvements in 10 revoluble stands or benches for supporting wash-tubs, or the like, and particularly to a stand adapted to be attached to and used in conjunction with suitable supports, such, for instance, as washing machines.

15 The sides of the tubs of washing machines now extensively in use are circular and afford a very slight hold for the attachment thereto of any sort of a stand of sufficient size to support a plain wash tub, such as is 20 generally employed in conjunction with such machines.

The object of my invention is to provide a contrivance of this kind which utilizes the body or legs of the washing machine tub to 25 sustain one end of it in such position under the wringer usually mounted upon the top of and overhanging one side of said tub that the end of the turn-table can be moved under it, and to which it can be removably attached whenever desired; which does not 30 take up as much room as an ordinary independent stand or bench, and which can be folded up and stored away. These and other advantages I obtain by the means 35 hereinafter fully described, and as particularly pointed out in the claims.

In the drawings: Figure 1 is a side elevation of my improved stand, attached to a suitable support such as a washing machine, 40 a fragment of which is shown to illustrate the manner of its attachment. Fig. 2 is a top plan view of said stand, showing a fragment of the leg of the support or washing machine to which it is attached. Fig. 3 is a vertical transverse section on line 3-3, Fig. 1, through the same looking in the direction indicated by the arrows. Fig. 4 is a detail section on line 4-4, Fig. 2, to illustrate the roller construction. Fig. 5 is a 45 detail section on line 5-5, Fig. 4, taken longitudinally through the roller. Fig. 6 is a detail view illustrating the joint or connection between the arms of the exten- 50 sion member of my improvements and the ends of the cross-bar connecting the same. 55 Fig. 7 is a view similar to Fig. 1, but including the upper part of the tub of the machine and the wringer thereof.

Referring to the drawings, A represents a fragment of a suitable support such as the 60 tub of a washing machine, B the supporting legs thereof, C the bracket secured to and overhanging the edge of the top of the machine and D the wringer mounted thereon.

My improved stand or bench consists of 65 an articulated frame and a turn-table mounted thereon. The articulated frame comprises a rectangular top member; a leg member pivoted to one end of said top member, and an extension member pivoted to 70 the opposite end of the top member. The top member consists of two parallel side-rails 1, 1; a transverse bar 2 connecting said side-rails at one end thereof, a second transverse bar 3 connecting said side-rails 75 near the opposite ends thereof and transverse boards 4, 5 and 6 connecting and fastened to the top edges of said side-rails.

The leg member, which is composed of 80 two side-bars or legs 7 and 8 that are connected by cross-bars 9 and 10, and are pivoted at their upper ends to the inner surface of side rails 1, 1, adjacent to transverse bar 2 by a transverse bar 11, which extends 85 through openings in the side rails 1, 1 and legs 7 and 8 and is secured in place by an enlarged head at one end thereof and a nut on the opposite screw-threaded end thereof. Legs 7 and 8 are recessed to provide shoulders *a* which, when the leg-member is in its 90 depending supporting position, engage the lower edge of transverse bar 2 and support the weight of the adjacent end of the stand. In its preferred construction, as illustrated, the extension member comprises two parallel arms 12, 12 which are pivoted at one end to the side rails of the top by a cross-bar 13, similar to cross-bar 11, hereinbefore referred to. The ends of these arms opposite their pivoted ends are provided with 100 vertically elongated attaching plates 14, the outer faces of which are in a plane oblique to the length of said arms so as to correspond to the plane of the outer surface of the support or legs of the tub of the machine 105 to which they are adapted to be attached.

These attaching-plates are provided with a plurality of suitably disposed bolt holes through which bolts 15 are fitted to secure the arms to said legs. I connect arms 12, 5 12, adjacent plates 14 by a cross rail 30, and for economy of construction, prefer to flare the ends of this cross-rail and secure the same to arms 12 by longitudinally disposed bolts 16 the barrels of which extend through 10 a longitudinal bore extending through bosses 17 located midway between the horns of the flared ends. The inner ends of said bolts screw into nuts 18 which latter are seated in openings 19 next the inner ends of 15 said bosses, and when suitable washers 20 are placed upon said bolts next the heads on the outer ends thereof and said bolts are sufficiently tightened, a strong and rigid connection between said arms and said cross 20 rail is secured. Constructing the extension member in this manner provides a knock-down construction, as the arms and cross bar may be dismounted by loosening and removing the bolts.

25 The turn-table 21 is, preferably, rectangular in shape and has slightly rounded ends, as shown, and when constructed of wood, it is reinforced and stiffened by transverse wooden cleats 22. This turn-table is 30 securely mounted upon a metal spider consisting of a central boss 32 and equi-distant arms 33 radiating therefrom that are screwed or bolted to the underside of said turn-table. A pivoted stud 24 depends from 35 boss 32 and is journaled in suitable bearing-plate 25 which latter is secured to the board 5, midway between the side rails 1, 1, of the top member. This stud extends down through its bearings and through a suitable 40 opening in board 5 and its involuntary withdrawal is prevented by a cotter-pin 26 fitted through a suitable opening in the lower end thereof.

The weight of the turn-table and its load 45 could be sustained by the engagement of boss 32 with the top of the bearings alone, but I prefer to give said turn-table greater stability and prevent it from developing a lateral tilt by providing an annular angle- 50 iron track 27 which is securely fastened upon the cross-boards 4, 5 and 6 of the top member concentric to the axis of the spider by means of screws 28 which are screwed through lugs 29 projecting inward from the 55 basal flange of said track into said boards.

A series of equi-distant casters are fastened to the underside of the turn-table that consist of screw-plates 34 having downwardly projecting lugs between which 60 rollers 31 are placed and revolvably mounted on bolts connecting said lugs. These casters are so placed that rollers 31 rest and travel on the upper edge of track 27.

In practice, it is usually desirable to at-

tach my improved stand to the legs of a 65 washing machine with one end of the turn-table of said stand located beneath the wringer, thereof so that the clothes can drop from the wringer into a tub or other suitable vessel support mounted on the end of 70 said table directly beneath it. When the tub is suitably filled, the table, if desired, can be turned or given half a revolution to bring another tub into operative position beneath the wringer, and the previously 75 filled tub can be carried to any desired place and a second tub substituted in its place on the table in readiness to be moved beneath the wringer. This greatly facilitates and expedites the operation of washing. 80

What I claim as new is:

1. The combination with a suitable support, of a stand having a frame composed of an intermediate top member and two end members, one of said end members being 85 adapted to be detachably secured to the support, the other end member being adapted to form a supporting leg, and a turn-table mounted on said top member.

2. The combination with a suitable support, of a stand having a frame composed of 90 flexibly connected members, one of said members being adapted to be detachably fastened to said support, another of said members being adapted to provide supporting 95 legs, and a turn-table rotatably mounted on said frame.

3. The combination with a suitable support, of a stand having a frame composed of an intermediate top member and two end 100 members, one of said end members being adapted to be disposed in an approximately horizontal position and detachably secured to the support, the other end member being adapted to form a supporting leg, and a 105 turn-table mounted on said top member.

4. A supporting stand comprising an intermediate or horizontally disposed top member, a horizontally disposed end member pivotally connected to one end of said 110 top member, and a vertically disposed leg member pivotally connected to and supporting the opposite end of said top member, a suitable vertically disposed bearing securely mounted on said top member, and a circular 115 track concentric thereto securely mounted on said top member, in combination with a turn-table provided with a downwardly projecting pivotal stud engaging said bearings, and suitable casters secured to the underside 120 of the turn-table and adapted to travel on said track.

5. A supporting stand comprising an intermediate or horizontally disposed top member, a horizontally disposed end member pivotally connected to one end of said 125 top member, and a vertically disposed leg member pivotally connected to and support-

ing the opposite end of said top member, and a suitable vertically disposed bearing securely mounted on said top member, in combination with a turn-table provided with a 5 downwardly projecting pivotal stud engaging said bearings.

In witness whereof I have hereunto set my hand this 6th day of January, 1915.

HOWARD W. POWER.
